US00D943422S

(12) **United States Design Patent** (10) Patent No.: **US D943,422 S**
(45) Date of Patent: **** Feb. 15, 2022**

(54) **STORAGE BAG**

(71) Applicant: **S.C. Johnson & Son, Inc.**, Racine, WI
(US)

(72) Inventors: **Charles P. Althoff**, Brooklyn, NY (US);
Keegan E. Burggren, Midland, MI (US); **Erica Eden Cohen**, New York, NY (US); **Brian C. Dais**, Saginaw, MI (US); **Imtiaz A. Musaliar**, Racine, WI (US); **Jose Porchia**, Greenfield, WI (US)

(73) Assignee: **S.C. Johnson & Son, Inc.**, Racine, WI (US)

(**) Term: **15 Years**

(21) Appl. No.: **29/755,013**

(22) Filed: **Oct. 16, 2020**

Related U.S. Application Data

(63) Continuation of application No. 29/660,320, filed on Aug. 20, 2018, now Pat. No. Des. 903,503, which is (Continued)

(57) **CLAIM**

The ornamental design for a storage bag, as shown and described.

DESCRIPTION

FIG. 1 is a front view of a storage bag showing our new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The shade lines in the figures show transparency or translucency.

The dashed broken lines in the figures show portions of the storage bag that form no part of the claimed design.

The dot-dash lines in the figures show boundaries that form no part of the claimed design.

1 Claim, 4 Drawing Sheets

Related U.S. Application Data

a continuation of application No. 29/624,615, filed on Nov. 2, 2017, now Pat. No. Des. 830,196, which is a continuation of application No. 29/600,737, filed on Apr. 14, 2017, now Pat. No. Des. 807,198, which is a continuation of application No. 29/546,346, filed on Nov. 20, 2015, now Pat. No. Des. 788,599, which is a continuation of application No. 29/510,704, filed on Dec. 2, 2014, now Pat. No. Des. 747,218, which is a continuation of application No. 29/449,559, filed on Mar. 15, 2013, now Pat. No. Des. 724,442, and a continuation of application No. 29/449,579, filed on Mar. 15, 2013, now Pat. No. Des. 723,939, and a continuation of application No. 29/449,596, filed on Mar. 15, 2013, now Pat. No. Des. 723,940, and a continuation of application No. 29/449,633, filed on Mar. 15, 2013, now Pat.
